US00D785590S

(12) **United States Design Patent** (10) Patent No.: **US D785,590 S**
(45) Date of Patent: ** May 2, 2017

(54) **MOBILE PHONE**

(71) Applicant: **LG ELECTRONICS INC.**, Seoul
(KR)

(72) Inventors: **Seala Park**, Seoul (KR); **Seungchul Cho**, Seoul (KR); **Woonlee Park**, Seoul (KR)

(73) Assignee: **LG ELECTRONICS INC.**, Seoul
(KR)

(**) Term: **15 Years**

(21) Appl. No.: **29/535,588**

(22) Filed: **Aug. 7, 2015**

(30) **Foreign Application Priority Data**

Feb. 10, 2015 (KR) 30-2015-0007090

(51) LOC (10) Cl. **14-03**

(57) **CLAIM**

The ornamental design for a mobile phone, as shown and described.

DESCRIPTION

FIG. 1 is a perspective view of a mobile phone showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a rear perspective view thereof.

(Continued)

The broken lines depict portions of the mobile phone that form no part of the claimed design.

1 Claim, 7 Drawing Sheets
